WALL-MOUNTED HEADBOARD FOR A BED

Kathleen Elliott, 220 E. 26th St.,
New York, N.Y. 10010

Filed Nov. 15, 1968, Ser. No. 14,487

Term of patent 14 years

Int. Cl. D6—01

U.S. Cl. D5—5

FIG. 1

FIG. 1 is a front view of a wall-mounted headboard for a bed showing my new design;

FIG. 2 is a top view thereof.

The back of the headboard is plain and unornamented.

I claim:

The ornamental design for a wall-mounted headboard for a bed, substantially as shown and described.
